(57) **CLAIM**

The ornamental design for a truck air intake bezel, as shown and described.

DESCRIPTION

FIG. 1 is a perspective view of a truck air intake bezel showing our new design;

FIG. 2 is a front view;

FIG. 3 is a top view;

FIG. 4 is right side view;

FIG. 5 is left side view; and,

FIG. 6 is a bottom view.

The rear of the air intake bezel is unornamented.

FIGS. 1–6 illustrate a first embodiment of our novel design suitable for use on the left of a truck hood. Our novel design also includes a second embodiment suitable for use on the right side of a truck hood which is mirror symmetrical to FIGS. 1–6 and therefore not separately illustrated.
